CLAIM

(21) Appl. No.: **29/187,552**

The ornamental design for a reinforcement bracket for automotive seat belt sleeve, as shown and described.

(22) Filed: **Aug. 4, 2003**

DESCRIPTION

(51) LOC (7) Cl. **02-07**

FIG. 1 is a side elevational view of a reinforcement bracket for an automotive seat belt sleeve embodying my new design;

(52) U.S. Cl. **D2/639**

FIG. 2 is a side elevational view thereof;

(58) Field of Search D2/627, 629, 639; D29/100, 101; D24/190; 297/467, 464, 468, 470, 481, 471, 482, 483, 487, 488; D11/200, 201, 218; 24/633; 280/732, 733

FIG. 3 is an end elevational view thereof;

(56) **References Cited**

FIG. 4 is a top plan view thereof;

U.S. PATENT DOCUMENTS

FIG. 5 is an end elevational view thereof; and,

5,442,840 A * 8/1995 Ewald 24/633
D387,887 S * 12/1997 Jensen D2/639

FIG. 6 is a perspective view in full lines with the broken lines showing of environmental association matter being for illustrative purposes only and forming no part of the claimed invention.
